UNITED STATES PATENT OFFICE.

JACOB SHANKS, OF ST. LOUIS, MISSOURI, ASSIGNOR OF ONE-HALF TO ISADORE FRY, OF ST. LOUIS, MISSOURI.

PHONOGRAPH ATTACHMENT FOR PLAYER-PIANOS.

1,130,350.

Specification of Letters Patent.

Patented Mar. 9, 1915.

Application filed January 3, 1914. Serial No. 810,265.

To all whom it may concern:

Be it known that I, JACOB SHANKS, a subject of the Czar of Russia, and resident of St. Louis, Missouri, have invented certain new and useful Improvements in Phonograph Attachments for Player-Pianos, of which the following is a specification containing a full, clear, and exact description, reference being had to the accompanying drawings, forming a part hereof.

My invention relates to improvements in phonograph attachments for player pianos, and the object of my invention is primarily to construct a phonographic attachment for player pianos which is wholly contained within the casing of the piano. And a further object of my invention is to arrange a connection between the driven roll of the piano player mechanism and the driven shaft of the phonographic attachment whereby a uniform speed of the phonograph obtains at all times regardless of the speed changes of the shaft of the player mechanism.

With the above purposes in view my invention consists in certain novel features of construction and arrangement of parts as will be hereinafter more fully described, pointed out in the claims and illustrated by the accompanying drawings, in which—

Figure 1 shows fragments of a piano casing with parts broken away to illustrate the relative arrangement of the parts of my phonographic attachment to the player mechanism; Fig. 2 is a fragmental plan of the piano casing partly in section showing the arrangement of the horn or megaphone of the phonograph; Fig. 3 is an enlarged detail front elevation showing the changeable speed connection between the player mechanism and the phonograph; Fig. 4 is an end elevation of the parts shown in Fig. 3; Fig. 5 is a longitudinal sectional elevation illustrating the clutch-mechanism employed in establishing or breaking connection between the player mechanism and the phonograph; and Fig. 6 is a fragmental elevation partly in section illustrating the clutch-operating device.

Referring by numerals to the accompanying drawings: 7 designates the casing which may be of any ordinary construction of a

player piano. Arranged within the piano casing 7 is an ordinary cabinet 8 and rotatably mounted in said cabinet is an ordinary driven shaft 9 and an idle shaft 10, the shaft 9 being rotated by the ordinary motor usually the pneumatic type (not shown). On each of the shafts 9 and 10 there are arranged the ordinary spools 11 which support ordinary perforated rolls 12. Associated with the player mechanism is a tempo control and indicator comprising in part the indicator proper 13, a rod 14 upon which the indicator is carried and which is arranged for lateral movements relative to the player mechanism, and a lever 15 for the manipulation of the indicator. All of these parts are or may be of the common and ordinary construction and arrangement.

The shaft 9 opposite its end connected with the motor projects some considerable distance through the cabinet 8 and supported upon said projecting end of the shaft is a cone-pulley 16 and secured to and rotatable with the cone-pulley is a clutch-member 17.

Referring to Fig. 5, it will be noted that there is extended through the shaft 9 a pin 18 which is embraced by the clutch-member in such manner that the clutch-member may rotate independently of the shaft and be held against axial movement relative to the shaft.

19 designates a movable clutch-member having diametrically opposite longitudinal slots 20 arranged to receive the ends of a pin 21 whereby the member 19 will at all times rotate with the shaft 9, yet be free to move axially thereof. The movable clutch-member is provided with a circumferential flange 22 arranged to be engaged by a device having a bifurcated end 23 and an enlarged manipulating end 24 for the operation of the movable clutch-member.

25 designates a standard which with the end of the cabinet 9 constitutes a support for a bracket 26 in which there is journaled a vertically disposed arbor 27 arranged for the support of a record disk support 28. Carried by the bracket 26 is a pintle 29 and horizontally alining with said pintle and also carried by the bracket 26 is an adjustable pintle 30. Supported by these two pintles is a shaft 31 carrying a cone-pulley 32

which cone-pulley is connected with the cone-pulley 16 by means of a belt 33.

Adjacent the cone-pulley 16 is a bearing 34 in which is pivotally mounted a belt shifter 35 which has its longest arm connected with the rod 14 of the tempo control and indicator.

Carried by the shaft 31 is a bevel gear wheel 36 arranged to mesh at all times with 10 a pinion 37 secured to rotate with the arbor 27.

It is to be observed that the front of the piano casing to one side of the music roll cabinet is perforated or grilled as shown at 15 38 in Fig. 2, and secured preferably to the end wall of the piano casing is a horn or megaphone 39, the open large end of which is next adjacent the perforated or grilled portion of the piano front. The horn has 20 associated therewith the usual pivoted arm 40 and the sound-box 41, both of which last mentioned elements are shown only by dotted lines in Fig. 2.

It will be readily understood from the 25 construction and arrangement of the parts as shown and described that the single motor of the player mechanism constitutes the driving means for the phonograph, and by the arrangement of the cone-pulleys in reverse 30 positions relative to each other and the belt connecting the pulleys that, when the tempo of the music is changed, the belt will be shifted to one end or the other of the cone carried by the driven shaft of the player 35 mechanism and, for the reason that the cone geared with the record support is in a reverse position relative to the first mentioned cone-pulley, that the speed of the record support is maintained approximately uniform 40 form, thereby causing the record of the

phonograph to reproduce at substantially the same rate of speed, at all times, as when the record was made.

I claim:

1. In combination with a player piano 45 mechanism having a tempo control, a phonograph, means including a reverse cone and belt drive connection between the player mechanism and the phonograph whereby, when the tempo of the player mechanism is 50 varied, the speed of the phonograph will be substantially uniform.

2. In combination with a player piano mechanism having a tempo control, a phonograph, and means including a variable speed 55 connection between said player mechanism and the phonograph connected with said tempo control whereby, when the tempo of the player mechanism is varied, the phonograph will operate at a substantially uni- 60 form speed.

3. In combination with a player piano mechanism having a tempo control, a phonograph, means including a variable speed connection between said player mechanism and 65 the phonograph connected with said tempo control whereby, when the tempo of the player mechanism is varied, the phonograph will operate at a substantially uniform speed, and means whereby said variable 70 speed connection may be thrown in and out of gear.

In testimony whereof, I have signed my name to this specification, in presence of two subscribing witnesses.

JACOB SHANKS.
